UNITED STATES PATENT OFFICE.

MARTIN T. AUSTIN, OF SIOUX FALLS, SOUTH DAKOTA.

ROAD-DRAG.

1,201,915.

Specification of Letters Patent. Patented Oct. 17, 1916.

Application filed May 4, 1916. Serial No. 95,420.

To all whom it may concern:

Be it known that I, MARTIN T. AUSTIN, a citizen of the United States, residing at Sioux Falls, in the county of Minnehaha 5 and State of South Dakota, have invented certain new and useful Improvements in Road-Drags, of which the following is a specification.

This invention relates to an improvement 10 in drags, and more particularly to such devices as are intended for and adapted to be used in straightening up and working over the top surface of roads.

An object of my invention is to provide 15 a drag which is so constructed that it may be horse drawn, or otherwise dragged over a roadway, and will cut down the sides of the road bed and bring the material thus accumulated to the center of the roadway, 20 thus building up the parts of the road which are naturally most cut and worn by use and at the same time giving the road bed the proper rise to shed water most efficiently.

25 A further object is to so construct the device that the material is not only cut from the sides of the road and brought to the center; but is also distributed and smoothed to give the desired smoothness to the road's 30 surface without further treatment to level the same, and to also construct the device in a manner that portions of the structure may be used or dispensed with as occasion may seem to require and a varied action in 35 the treatment of the road or surface can be accomplished.

With the above and other objects in view, 40 my invention consists in certain novel features of construction and combinations of parts which will be hereinafter set forth in connection with the drawings and then more particularly pointed out in the claims.

In the drawings: Figure 1 is a top plan view of the structure. Fig. 2 is a longitudinal vertical sectional view taken on the line 2—2 of Fig. 1. Fig. 3 is a view taken in section on the line 3—3 of Fig. 1. Fig. 4 is a view in perspective of a structural member of the device.

45 The side scrapers 1 and 2 are continued in the scraper members 3 and 4 which are joined thereto by the frame structure to be hereinafter more fully described, and these drag or scraper members are arranged to 50 form the side scraper bar 5 constituting the members 1 and 3, and the side scraper

bar 6 formed from the members 2 and 4, these side scraper bars 5 and 6 being brought together at their rear ends in an apex and made convergent therefrom to be disposed 60 substantially at right angles. The abutting ends of the side scraper bars 5 and 6 are secured together by the means of rivets 7, or in any other desired manner and cross frame members 9 and 10 are secured between the side scraper bars 5 and 6 to hold 65 the same rigidly mounted in the desired angular disposition, the longitudinally extending frame members 11 and 12 being mounted between the transversely disposed frame members 9 and 10 to give additional 70 bracing and support to the entire structure.

A cross brace 13 is connected between the spread ends of the side scraper members 3 and 4 which are brought together to form 75 the apex 14 of the side scraper bars 5 and 6, and thus these members 3 and 4 are connected together as a unit, the bolts 15 being used to secure the member 3 in alinement with the member 1 and the bolts 16 being 80 used at the opposite side of the structure to secure the member 4 in line with the scraper member 2 so that by the removal of the bolts 15 and 16, the structure comprising the side scraper members 3 and 4 85 and the cross brace 13 may be removed from its connection with the remaining elements, and the cross member 13 will form a frame structure to hold the side scraper members 3 and 4 in the proper relation, while the 90 side scraper members 1 and 2 will be held in the proper relation by the transversely extending frame members 9 and 10. To give additional support to the extreme outer end of the side scraper members 1 and 2, it 95 is preferable that the brace bars 17 and 18 be connected between the ends thereof and the cross frame member 9, and it is also perhaps desirable that the forward ends of the scraper members 1 and 2 be curved or 100 rounded off as at 19 so that the four corners will not dig into the earth when the machine is being dragged over a road, but rather the action will be a dragging action throughout the entire extent of each of the 105 side members 5 and 6.

Draw bars 20 and 21, the construction of which is better shown in Fig. 4, are brought together at their forward ends and are connected by a link 22 with the transverse frame 110 member 9, the connection being at the approximate center of this member and the

draw bars 20 and 21 being extended in divergent disposition rearwardly and connected with the drag bar 23 at each end of the same. Links 24 and 25 are connected 5 with the ends of the drag bar 23 and are extended forwardly and are connected with the cross frame member 9, this connection with the links 24 and 25 as well as the connection with the link 22 being such that the 10 drag bar 23 and the draw bars 20 and 21 connected therewith are permitted to have free swinging movement with respect to the frame member 9.

Suitable hitch loops or eyes 26 and 27 are 15 connected with the cross frame member 9 at the ends thereof and drag chains 28 and 29 are connected in these loops or eyes and at their free ends are connected in a hitch ring 30, this ring being provided to permit 20 a draft hitch to the machine. A ring 31 is connected in the apex 14 of the drag or scraper bars and thus by establishing a hitch between the ring 30 of one machine and the ring 31 of a second device, the drags may 25 be hitched to travel in gangs where it is desired to give a second treatment to the road, this necessitating only passage of the devices over any particular strip of the road.

In the use of the device, when the parts 30 are connected, as is shown in the illustration in the drawings, the hitch is accomplished through the ring 30 and as the drag is moved forward in the direction indicated by the arrow of Fig. 1, the forward rounded corners 35 19 of the scraper members 1 and 2 will ride over the surface of the road and these members 1 and 2 will drag to take up loose earth and to level any obstructions or rises in the road bed, and due to the fact that the side 40 scraper members 5 and 6 are angularly disposed to be convergent rearwardly, the material scraped up or dragged from the road will be directed inwardly and the drag member 23 will pass this portion of the material 45 and will at the same time act through its own initiative to treat the central portion of the road, this drag bar due to the fact that it is disposed transversely of the machine acting to distribute the material as 50 conducted thereto by the angularly disposed side scraper bars 5 and 6 and to level the center of the road, however, a portion of the loose earth taken up by the bars 5 and 6 will escape the drag bar 23 and the scraper 55 members 3 and 4 will catch this earth and will cause distribution of the same in the center of the road way. It will of course be understood that when the side scraper members 3 and 4 are removed through the release 60 of the bolts 15 and 16, the action will be accomplished solely through the members 1 and 2 and the drag bar 23, however, it has been found that a more efficient action is attained where the members 3 and 4 are also 65 used. Where two or more of the devices are

hitched to be drawn one following the other, it will be understood that the forward machine might have the members 3 and 4 secured in place and the last machine might have the members removed, and also that 70 devices of various sizes, that is, having various widths, and also perhaps having the angularity or the size thereof varied, might be connected, and thus a rough action might be obtained by the first machine and a finishing action by the last machine of the gang hitched to give the constructive treating working to the road. Where desired, the hitch might be made to a power tractor or 80 to any other power draft means and where this is done, a number of machines might be hitched so that they would trail and thus a very thorough working of the road might be accomplished.

A shaft 32 is mounted on the frame member 9 and then has the offset bearing portions 33 and 34 which portions have the carrying wheels 35 and 36 mounted rotatably thereon, and a shaft 37 mounted near the apex 14, has the offset bearing portion 38 provided therein and has a carrying wheel 39 mounted on this offset bearing portion. An operating lever 40 is pivotally mounted on the frame member 12 and has the lower projecting end 41 thereof connected with arms 42 and 43 carried by the shafts 32 and 37, through the medium of the links 44 and 45. An arcuated rack 46 is provided to permit setting of this lever 40, and thus the carrying wheels 35, 36, and 39 may be either raised to be entirely out of contact with the road bed to permit action of the device as a drag, or these carrying wheels may be swung to the relation shown in Figs. 2 and 3 and the device will then be 100 supported and carried with the side bars 5 and 6 entirely above the surface over which the machine is being moved.

While I have herein shown and described only one specific form of the device, it will 110 be understood that the arrangement of the carrying wheels together with the means for operating the same, the connection of the frame and bracing structures and other parts might be varied, and also that a number of changes in the structure might be resorted to as demanded by conditions concurrent with the particular adaptation of the device, and I therefore desire to reserve the right to resort to such changes in the 115 details of construction, proportion and arrangement of parts, as may be necessary without sacrificing any of the advantages of my invention, in so far as these variations may be set forth in the claims.

I claim:

1. A drag comprising side bars secured together in angularly disposed relation with the rear ends abutting in an apex, a cross frame member connected between the spread 130

ends of said side bars, a hitch by which the device may be moved forward with the apex of the side bars trailing, a drag bar having an elongated scraping edge, and links connecting said drag bar and the cross frame member to mount the drag bar between the side bars forwardly of the apex and in a position at right angles to the line of movement of the device as it is drawn.

10 2. A drag comprising a pair of scraper members angularly disposed with the proximate ends thereof spaced apart, a hitch by which said drag may be drawn forward with the spread ends of said members forward, a drag bar mounted between the angularly disposed members to extend across the opening between the spaced proximate ends of said members, and extension scraper members connected with said angularly disposed members to continue the lines thereof and having their inner ends connected together in an apex to form a structure supplementing the action accomplished by the drag bar.

25 3. A drag comprising a pair of side scraper members arranged in angular disposition with the proximate rear ends thereof spaced apart, transversely extending frame members connected between said scraper members to mount the same rigidly and maintain the angular and spaced disposition thereof, draft attaching means by which the device may be drawn forward with the spread ends of the scraper bars foremost, a drag bar, links pivotally connecting said drag bar with one of the transversely extending frame members to dispose said bar across the opening between the rear ends of the side scraper members, said drag bar being of greater extent than the opening be-

tween the rear ends of the side scraper members to receive material as taken up by said scraper members and accomplish an equal distribution of the material through the opening between the side members, extension side scraper members connected in angular disposition with the rear ends thereof secured together to form an apex and the forward ends connected in separated relation corresponding to the separation of the side scraper bars, and means by which said extension scraper members are connected to the side scraper members to form a substantial continuation thereof and to accomplish an additional treating action over the action attained by the drag bar.

4. A drag comprising a pair of side scraper bars arranged in angular disposition with the proximate rear ends thereof abutting in an apex, a cross frame member connected between the spread ends of said side bars, a hitch connected rearwardly of the spread ends of said side bars by which the device may be moved forwardly with the apex trailing, a drag bar of less longitudinal extent than the space embraced between the spread ends of the side bars located within the angle of said bars forwardly of the apex, and links connected from said drag bar to the cross frame member to permit movement of the bar in a swinging path between the side bars and to allow the same to be moved by gravity to a position to drag upon the surface over which the drag is being drawn.

In testimony whereof I affix my signature in presence of two witnesses.

MARTIN T. AUSTIN.
